UNITED STATES PATENT OFFICE

CHARLES C. TOMKINSON, OF PLAINFIELD, NEW JERSEY, ASSIGNOR, BY MESNE ASSIGNMENTS, TO J. EDWARD OGDEN COMPANY, OF NEW YORK, N. Y., A CORPORATION OF NEW JERSEY

DOOR CLOSURE AND OPERATING MECHANISM

Application filed April 4, 1928. Serial No. 267,166.

This invention relates to operating and control mechanism for doors and particularly for elevator hatchway doors.

The invention has for its salient object to provide simple and practical door operating mechanism for opening or closing one or a plurality of hatchway doors.

Another object of the invention is to provide door operating structure so constructed and arranged that a plurality of doors in an elevator hatchway can be controlled through a single operating element.

Another object of the invention is to provide door locking mechanism so constructed and arranged that a door locked thereby cannot be accidentally opened.

Another object of the invention is to provide in conjunction with door operating mechanism, means operative when the door is opened to store up power to assist in the closing of the door.

Another object of the invention is to provide intercontrol means for hatchway doors so constructed and arranged that the doors for hatchway openings on adjacent floors can be operated simultaneously or independently.

Further objects of the invention will appear from the following specification taken in connection with the drawings, which form a part of this application, and in which

Fig. 1 is a sectional elevation illustrating a plurality of hatchway doors and operating mechanism therefor;

Fig. 2 is a sectional elevation taken at right angles to Fig. 1;

Fig. 3 is a transverse sectional elevation illustrating the door construction;

Fig. 4 is a sectional elevation showing the counterweight sheaves and connections to the door;

Fig. 5 is a detail elevation illustrating one form of abutment for supporting the counterweights;

Fig. 6 is a view similar to Fig. 5 showing

a slightly different form of counterweight supporting abutment;

Fig. 7 is a plan view of one of the disks shown in Fig. 6 and adapted to provide for adjustment in the counterweight supporting abutment;

Fig. 8 is an enlarged sectional elevation illustrating a door locking or latching mechanism;

Fig. 9 is a sectional elevation taken through the bottom edge portion of the door illustrating a self-adjusting flap carried by the bottom of the door;

Fig. 10 is a sectional elevation of one edge portion of the door showing the guide rail;

Fig. 11 is a view taken at right angles to Fig. 10, illustrating a spring at the end of the guide rail or track for storing up energy when the door is opened;

Fig. 12 is a view similar to Fig. 1 but illustrating separate operating mechanism for alternate floors;

Fig. 13 is a diagrammatic view taken at right angles to Fig. 12.

The invention briefly described consists of a door operating mechanism comprising a single element adapted to control the operation of a plurality of hatchway doors and controlled in its movement by hydraulic or pneumatic operating mechanism. In the form of the invention disclosed, each door is adapted to be opened by counterweighting mechanism and it is adapted to be closed when the counterweighting mechanism is raised or supported by the control elements.

Each door is furthermore provided with means for storing up energy when the door is opened to assist in the initial closing movement thereof.

Various forms of door operating connections are shown but in each form of the invention a single element extending through the shaftway controls the opening and closing of the doors and, furthermore, in each case adjustable connections are provided for

the purpose of insuring the desired movement of the door from open to closed position and vice versa.

5 The invention also includes electric control connections whereby doors at adjacent floors can be simultaneously controlled or independently controlled.

Further details of the invention will appear from the following description.

10 *Door closure construction*

In the form of the invention illustrated in Figs. 1 and 2, there are shown a plurality of floor levels A, B, C and D. At each of 15 the floor levels there is a hatchway door opening 20 adapted to be closed by a door which, as illustrated, comprises a pair of sections 21 and 22 hingedly connected at 23.

The door sections are provided at their 20 lateral edges with rollers 25, 26 and 27 positioned in channel tracks or guide rails 29 and 30. The guide rails are provided with vertical portions 35, curved, intermediate portions 36 and horizontal portions 37. Each of 25 the horizontal portions of the tracks has a spring 38 mounted in the end thereof adapted to be compressed when the doors are moved to their wide open position, as shown at Fig. 2, at the floor levels B and C.

30 The springs 38 store up energy when the doors are opened and assist in the initial closing movement of the doors when the doors are closed.

Each door is adapted to be opened by a 35 counterweight 40 having a pair of lugs or brackets 41 and 42, between which are mounted a pair of sheaves 43 and 44. A counterweight cable 45 has one end secured as shown at 46 to a fixed support and the cable passes 40 beneath sheave 43, upwardly over a sheave 50 and downwardly to a bracket or lug 51 to the lower end of one of the side edges of the lower door section 21. A fusible link 52 is preferably interposed between the lower 45 end of the cable and the lug or bracket 51.

Another counterweight cable 53 is also secured to a fixed support and passes under the counterweight sheave 44, upwardly over a sheave 55 and across the door opening, around 50 a sheave 56 and downwardly to a bracket or lug 57 projecting laterally from the opposite edge of the lower door section 21. A fusible link 58 is interposed between the lug 57 and the lower end of the cable 53.

55 The counterweight 40 is of sufficient weight to raise the door sections to open position when the weight is free to fall and by reason of the counterweight cable connections above described it will be clear that the counterweight will move only one-half the distance 60 of the door sections.

From the showing in Fig. 2 it will be noted that the door section 21 in its wide or open position is inclined. Since there is comparatively little friction and the movement of the

door section 22 along the horizontal portions of the guide rails requires only a small amount of force, when the counterweight is lifted the doors will move of their own weight to closed position. The initial movement, as above stated, is assisted by the springs 38 which store up energy when the door is opened. A bumper 39 is secured adjacent the lower end of each door section 21 and, as shown in Fig. 3, extends over the two edges of the door for the purpose of protecting the guide rails 29 and 30.

70 *Operating mechanism for door closures*

The operating mechanism is so constructed 80 and arranged that a plurality of hatchway doors can be opened simultaneously or any one of the doors that is unlocked can be opened individually. This statement also applies to the closing of the doors. In Figs. 1 85 and 2 the doors at floor levels B and C are open and the door at the floor level A is closed. When the counterweights 40 at the floor levels B and C are raised, the doors at 90 these floor levels will be closed.

The counterweights are controlled by a single cable 60 which, in the form of the invention illustrated, is secured through a turnbuckle 61 to a rod 62 having mounted on the upper end thereof a piston 63 in a 95 cylinder 64. An adjustable stop 59 is provided at one end of the cylinder 64.

The cable 60 has secured thereto vertically spaced clamps 65. In the form of the invention illustrated in Figs. 1, 2 and 5, each clamp 100 has threaded therein a sleeve 66 having a head 67. A spring 68 is interposed between the head 67 of each sleeve and the counterweight 40 controlled thereby and by adjusting the sleeve 60 the operation of the counterweight 105 raising and lowering element can be so regulated as to properly control the movement of the door to open and closed positions.

In Figs. 6 and 7 a plurality of slotted disks or washers 70 are positioned between the 110 clamps 65 and the spring 68. Each washer has a central opening 71 for receiving the cable 60 and has a slot 72 leading from the opening 71 to the periphery of the washer. The cable 60 and rod 62 are raised and lowered by hydraulic operating means for the cylinder 64. A conduit 75 conducts hydraulic pressure fluid to a valve casing 76 having a valve 77 therein provided with passages 78 and 79. The casing 76 has a pair of outlet conduits 80 and 81. Conduit 80 communicates with a pair of conduits 85 and 86 and conduit 81 communicates with a pair of conduits 87 and 88. Conduits 85 and 86 communicate with the cylinder 64 adjacent one end 115 thereof and conduits 87 and 88 communicate with the cylinder adjacent the other end thereof, it being noted that the conduits 86 and 87 are disposed nearer the longitudinal center of the cylinder than the conduits 85 120 and 88.

and 88. Casing 76 has a discharge conduit 89 connected thereto and adapted to conduct the pressure fluid away from one or the other end of the cylinder.

5 The valve 77 has a spindle 95 provided with an arm 96 which is connected by a pin slot connection to a rod 97 which in turn is adapted to be moved in opposite directions by a pair of solenoids 98 and 99.

10 The conduits 85, 86, 87 and 88 are each provided with a regulating valve 100 for controlling the passage of the fluid through the conduits. In Fig. 1 it will be seen that the pressure fluid has been fed into the upper end 15 of the cylinder 64, through the conduit 75, passage 78, conduit 80 and conduits 85 and 86. On the other hand, the lower end of the cylinder is open to the exhaust conduit 89, through the passage 79, conduit 81 and conduits 87 and 88. When the solenoid 98 is energized, the rod 97 will be moved upwardly, viewing Fig. 1, thus rotating the valve 77 and opening the conduit 81 to the incoming pressure fluid and opening the conduit 80 to the 20 exhaust conduit 89. Thus, the piston 63, rod 62 and cable 60 will be raised.

25 The valves 100 in the conduits 85 and 88 are so regulated that the passage of the fluid through these conduits is restricted. When the valve is reversed and the conduit 81 is placed in communication with the pressure conduit 75, the pressure fluid will first pass through the conduit 88 and raise the piston slowly until the conduit 87 is uncovered by 30 the piston, whereby the piston will be raised more rapidly. During the upward movement of the piston, both conduits 85 and 86 will conduct the pressure fluid above the piston away from the cylinder until the piston 63 35 overlaps the intake end of the conduit 86.

40 Thereafter the discharge of the fluid will take place through the conduit 85 and this discharge will be at a slower rate of speed, thus providing a cushioning effect. To assist in the downward movement of the cable 60, a counterweight 101 is secured to the lower end of the cable and may be located in the 45 basement of the building.

45 Means is provided in connection with each door for locking the door in closed position, the locking means being so constructed that the release of a counterweight controlling a door will not open the door unless the locking means has been previously released. The 50 locking means is particularly illustrated in Fig. 8, wherein the upper end of a door section 22 is shown as provided with a recess 110 having a casing 111 positioned therein. The casing has an upwardly extending flange 55 112 adapted to engage a notch 113 formed in the lower edge of a reciprocable latch 114 having a beveled outer end 115. The latch 114 is slidably mounted in a casing 116 carried by the door casing 120. A spring 121 60 tends to force the latch 114 outwardly and a

65 solenoid winding 122 surrounds each of the latches and is adapted, when energized, to withdraw the latch. When the counterweights are raised by the cable 60, thus permitting the doors to close, the latches will 70 snap into the casings 111. Thereafter, when the cable 60 is lowered to withdraw the abutments from the counterweights for the purpose of opening one or more doors in the shaft, the counterweight of each unlocked 75 door will raise the door to cause the flange 112 to enter the notch 113. This will prevent any accidental withdrawal of the latch and thus any accidental opening of the door.

80 Each door has pivoted to the bottom thereof, a flap 118 for the purpose of closing the crack below the door when the door has been raised by its counterweight to cause the flange 112 to enter the notch 113 of the lock.

85 Figs. 12 and 13 illustrate an arrangement particularly adapted for use in connection with double-decked elevators or, in other words, for use with elevators serving a plurality of floors at the same time.

90 It has been found that a single door operating mechanism or element for opening and closing hatchway doors is subject to certain disadvantages when used in connection with a double-decked elevator. For instance, when the elevator is disposed in position to serve 95 two floors, and it is desired to open the hatchway doors at those two floors, they cannot be opened consecutively or successively but must be opened simultaneously. If the operator has already unlocked and opened the 100 door at one of the floor levels served by the elevator and then desires to open the door at the other floor level, this cannot be done without first closing the door which has already been opened, since the release of the 105 latch of the closed door would permit this door to open with a bang rather than gradually. Furthermore, in most cases difficulty is 110 encountered in releasing the latch after the counterweight control element has moved away from the counterweight of the closed door.

115 To overcome the difficulties set forth in the preceding paragraph, means has been provided in the form of the invention illustrated in Fig. 12 for independently controlling the opening of doors at adjacent floor levels. In this embodiment of the invention a power cylinder X controls the raising and lowering element 170 which in turn controls the raising and lowering of the counterweights for the doors at floor levels A and C. A second power cylinder Y controls the raising and lowering element 171 which in turn controls the opening of the door at floor level B and would also 120 control the opening of the door at the floor level above the floor D if this floor level and the door therefor were illustrated.

125 Since the operation of the cylinders X and Y and the connections for opening and clos- 130

ing the doors are the same in Fig. 12 as those already described, further description is not deemed necessary. With the construction illustrated in Fig. 12 if the two decks of the car are disposed opposite floor levels B and C, then the doors at these floor levels can be opened independently and it will not be necessary to open them simultaneously.

From the foregoing description it will be seen that simple, practical and effective means have been provided for opening and closing hatchway doors. By means of the mechanism described, one or a plurality of the doors can be operated simultaneously and, furthermore, the control mechanism for the opening and closing of the doors is so constructed and arranged that this mechanism will cooperate with the doors in a manner to insure the correct amount of travel or movement of the doors.

Moreover, means has been provided in conjunction with the door operating means for storing up energy when the doors are opened for assisting in the initial closing movement of the doors.

Door latching means has been provided for preventing accidental opening of the door after the supporting means for the counterweight which controls the opening of the door has moved away from the counterweight. The form of the invention illustrated in Fig. 12, as above described, is particularly adapted for use in conjunction with double-decked elevators and by means of this construction the doors at adjacent floor levels are independently controlled.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. Door closure and operating mechanism comprising a plurality of hatchway doors movable to open and closed positions, operating and control means for said doors for controlling the opening and closing movements of doors on alternate floors, and other means for controlling the movements of the other doors.
55. 2. Door closure and operating mechanism comprising a plurality of hatchway doors movable to open and closed positions, reciprocatable control means for controlling the opening and closing movements of doors on alternate floors, and other reciprocatable control means for controlling the movements of the other doors.
60. 3. In combination, door closure and operating means comprising a plurality of hatchway doors movable to open and closed posi-

tions, a double-deck elevator adapted to serve two adjacent floor levels, and independent, power operated door control mechanisms for effecting the opening and closing of the hatchway doors at adjacent floor levels so that the hatchway doors at two floor levels served by the two decks of the elevator can be controlled and operated entirely independently of each other.

4. In combination, door closure and operating means comprising a plurality of hatchway doors movable to open and closed positions, a double-deck elevator adapted to serve two adjacent floor levels, and independent pressure operated door control mechanisms for effecting the opening and closing of the hatchway doors at adjacent floor levels so that the hatchway doors at two floor levels served by the two decks of the elevator can be controlled and operated independently of each other.

5. In combination, a door movable to open and closed positions, a counterweight operatively connected to the door for opening the door, means for supporting said counterweight to prevent the opening of the door thereby, said means being movable downwardly to permit the counterweight to open the door, a latch for retaining the door in closed position, the latch and door having parts adapted to coact to prevent the withdrawal of the latch when the counterweight is unsupported.

6. In combination, a door movable to open and closed positions, a counterweight operatively connected to the door for opening the door, means for supporting said counterweight to prevent the opening of the door thereby, said means being movable downwardly to permit the counterweight to open the door, a latch for retaining the door in closed position, the latch and door having parts adapted to coact to prevent the withdrawal of the latch after the counterweight supporting means has moved downwardly and permitted the counterweight to be lowered.

7. In combination, a door movable to open and closed positions, a counterweight operatively connected to the door for opening the door, means for supporting said counterweight to prevent the opening of the door thereby, said means being movable downwardly to permit the counterweight to open the door, a latch for retaining the door in closed position, and means including a notch and a projection for preventing the withdrawal of the latch when the counterweight is unsupported.

8. In combination, a pair of tracks, a door movable in said tracks to open and closed positions, means for moving the door to open position, and a bumper carried by the door and having portions overlapping said tracks.

9. In combination, a door movable to open

and closed positions, a counterweight operatively connected to the door for opening the door, means for supporting said counterweight to prevent the opening of the door thereby, said means being movable downwardly to permit the counterweight to open the door, a latch for retaining the door in closed position, said latch and door being so arranged that the door can be raised a slight amount when the latch is in latching position, and movable means at the bottom of the door for closing the crack when the door is so raised.

10 10. Door closure and operating means comprising a plurality of hatchway doors disposed at different floor levels and movable to open and closed positions, and two sets of door control mechanisms, each set being arranged to control the doors at alternate 20 floor levels, each of said mechanisms being operable independently of the other set whereby the doors at one floor level can be operated independently of the doors at the adjacent floor levels.

25 11. Door closure and operating means comprising a plurality of hatchway doors disposed at different floor levels and movable to open and closed positions, and two sets of door control mechanism, one set being 30 constructed and arranged to control the doors at the odd floor levels and the other set being constructed and arranged to control the doors at the even floor levels.

35 12. In combination, door closure and operating means comprising a plurality of hatchway doors located at different floor levels, a double deck elevator adapted to serve two adjacent floor levels, two sets of 40 control mechanisms for said doors, one set being connected to control the doors at the odd floor levels and the other set being connected to control the doors at the even floor levels, whereby the doors at the two floor 45 levels served by the two decks of the elevator can be operated entirely independently.

In witness whereof, I have hereunto set my hand this 2nd day of April, 1928.

CHARLES C. TOMKINSON.
